EAR EMBRACING HEARING AID OR SIMILAR ARTICLE

Barkman C. McCabe and John R. Foss, Los Angeles,
Calif., assignors to Burglar Blast, Inc., Los Angeles,
Calif.

Filed Oct. 30, 1969, Ser. No. 19,850

Term of patent 14 years

Int. Cl. D2—03

U.S. Cl. D2—259

FIG. 1 is a perspective view of an ear embracing hearing aid or similar article showing our new design;

FIG. 2 is a front elevational view thereof;

FIG. 3 is a rear elevational view thereof;

FIG. 4 is a side elevational view thereof;

FIG. 5 is a side elevational view thereof showing the side opposite that shown in FIG. 4; and

FIG. 6 is a bottom plan view thereof.

The top of the ear embracing hearing aid or similar article is substantially a mirror image of the bottom as shown in FIG. 6, the top being shown in part in each of FIGS. 1, 3, 4 and 5.

We claim:

The ornamental design for an ear embracing hearing aid or similar article, as shown and described.
